US0D1029067S

(12) **United States Design Patent** (10) **Patent No.:** **US D1,029,067 S**
(45) **Date of Patent:** **** May 28, 2024**

(54) **SUPPORTING UNIT OF WAREHOUSING ROBOT**

(71) Applicant: **HAI ROBOTICS CO., LTD.**,
Guangdong (CN)

(72) Inventor: **Jin Jiang**, Guangdong (CN)

(73) Assignee: **HAI ROBOTICS CO., LTD.**,
Shenzhen (CN)

(**) Term: **15 Years**

(21) Appl. No.: **29/833,170**

(22) Filed: **Apr. 1, 2022**

(30) **Foreign Application Priority Data**

Oct. 20, 2021 (CN) 202130688680.1

(51) **LOC (14) Cl.** **15-99**

(52) **U.S. Cl.**

USPC **D15/199**

(57) **CLAIM**

The ornamental design for a supporting unit of a warehousing robot, as shown and described.

DESCRIPTION

FIG. 1 is a front view of a supporting unit of a warehousing robot showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof; and,

FIG. 8 is a second perspective view thereof.

The broken lines shown in the drawings represent portions of the supporting unit of a warehousing robot that form no part of the claimed design.

1 Claim, 8 Drawing Sheets
